UNITED STATES PATENT OFFICE

146,308

DESIGN FOR A COMBINED SHOWER HEAD
AND WATER TEMPERATURE INDICATOR

Slingsby D. Harman, Galesburg, Ill.

Application February 14, 1946, Serial No. 126,557

Term of patent 14 years

(Cl. D91—1)

To all whom it may concern:

Be it known that I, Slingsby D. Harman, a citizen of the United States, residing at Galesburg, in the county of Knox and State of Illinois, have invented a new, original, and ornamental Design for a Combined Shower Head and Water Temperature Indicator, of which the following is a specification, reference being had to the accompanying drawing, forming a part thereof.

Fig. 1 is a plan view of a combined shower head and water temperature indicator showing my new design;

Fig. 2 is a side elevation thereof; and
Fig. 3 is a front elevation thereof.

I claim:

The ornamental design for a combined shower head and water temperature indicator, as shown.
SLINGSBY D. HARMAN.
